UNITED STATES PATENT OFFICE.

THEODORE W. FOSTER, OF PROVIDENCE, RHODE ISLAND.

DESIGN FOR A BREASTPIN.

SPECIFICATION forming part of Design No. 15,534, dated November 11, 1884.

Application filed July 31, 1884. Term of patent 7 years.

To all whom it may concern:

Be it known that I, THEODORE W. FOSTER, a citizen of the United States, residing at Providence, in the State of Rhode Island, have invented and produced a new and original Design for a Jewelry Pin, of which the following is a specification, reference being had to the accompanying drawings, forming a part thereof.

Figure 1 is a front view of my newly-designed jewelry pin. Fig. 2 is an edge elevation of the same. Fig. 3 is an end view. Fig. 4 is a longitudinal section, these four views being deemed necessary to fully illustrate my design.

The leading feature of my design consists in a front plate the outline and front surface of which represent a broom and its handle, the outline edge of the broom being turned backward from its striated front, and having a smooth appearance.

In the accompanying drawings, A is the front plate of a jewelry pin having the form of a broom and its handle, the broom portion *a* of which is grooved or ridged lengthwise to represent the fiber of the broom, and having its outline edge *b* turned backward from its front, the turned edge having a contrasting smooth appearance with the striated front surface of the broom.

I claim—

The design for a jewelry pin herein shown and described, the same consisting of a plate having the shape of a broom and its handle, the broom portion of the plate having lengthwise grooves and ridges, and also having a smooth backwardly-turned edge.

THEODORE W. FOSTER.
